**COMBINED 8-TRACK TAPE TRANSPORT,
AMPLIFIER AND TUNER THEREFOR**

Naoki Tominaga, Osaka, Japan, assignor to Sanyo
Electric Co., Ltd., Osaka, Japan

Filed June 28, 1971, Ser. No. 157,798

Term of patent 14 years

Int. Cl. D14—03

U.S. Cl. D26—14

FIG. 1

FIG. 2

FIG. 3

FIG. 1 is a top, right hand, front perspective view of a combined 8-track tape transport, amplifier and tuner therefor showing my new design;

FIG. 2 is a bottom, rear, right hand perspective view thereof; and

FIG. 3 is a left hand side elevational view thereof.

I claim:

The ornamental design for a combined 8-track tape transport, amplifier and tuner therefor, as shown in the drawings.
